(57) **CLAIM**

The ornamental design for a rail guard for electric vehicle, as shown and described.

DESCRIPTION

FIG. 1 is a perspective view of the new design for a rail guard for electric vehicle, according to a first embodiment; FIG. 2 is a front view thereof;

FIG. 3 is a left side view thereof;

FIG. 4 is a right side view thereof;

FIG. 5 is a top view thereof;

FIG. 6 is a bottom view thereof;

FIG. 7 is another view of FIG. 2, showing an illustration of use on an electric vehicle;

FIG. 8 is a perspective view of the new design for a rail guard for electric vehicle, according to a second embodiment;

FIG. 9 is a front view thereof;

FIG. 10 is a left side view thereof;

FIG. 11 is a right side view thereof;

FIG. 12 is a top view thereof;

FIG. 13 is a bottom view thereof; and,

FIG. 14 is another view of FIG. 9, showing an illustration of use on an electric vehicle.

The dash-dash broken lines shown in the drawings illustrate portions of the rail guard for electric vehicle that form no part of the claimed design.

The dash-dot broken lines in FIG. 7 and FIG. 14 are included for the purpose of illustrating an example environment and form no part of the claimed design.

The rear of the rail guard for electric vehicle is not part of the claimed design, and so the rear view has been omitted. The shading lines shown in the drawings represent the approximate three-dimensional contour of the design, and are not intended to indicate surface decoration.
